UNITED STATES PATENT OFFICE

123,640

DESIGN FOR A GASOLINE SERVICE STATION BUILDING

Paul E. Thomason, Charlotte, N. C.

Application September 14, 1940, Serial No. 95,053

Term of patent 14 years

To all whom it may concern:

Be it known that Paul E. Thomason, a citizen of the United States of America, residing at Charlotte, in the county of Mecklenburg and State of North Carolina, has invented a new, original and ornamental Design for a Gasoline Service Station Building, of which the following is a specification, reference being had to the accompanying drawing, forming a part thereof.

Figure 1 is an isometric view of a gasoline service station building looking at the front and one end thereof, embodying my design;

Figure 2 is an isometric view looking at the rear and the other end thereof;

I claim:

The ornamental design for a gasoline service station building, as shown.

PAUL E. THOMASON.
